(57) **CLAIM**

The ornamental design for an electronic washing machine, as shown and described.

DESCRIPTION

FIG. 1 is a front perspective view of the electronic washing machine showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a reference view showing the state of use that the hidden display at the front right upper part has been operated.

The broken lines depict portions of the electronic washing machine that form no part of the claimed design.

1 Claim, 8 Drawing Sheets
